(57) **CLAIM**

The ornamental design for a binder, as shown and described.

DESCRIPTION

FIG. 1 is a front perspective view of a binder, showing my new design in a closed state;

FIG. 2 is rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a partial enlarged view of portion 9 shown in FIG. 1;

FIG. 10 is a partial enlarged view of portion 10 shown in FIG. 1;

FIG. 11 is a partial enlarged view of portion 11 shown in FIG. 2;

FIG. 12 is a partial enlarged view of portion 12 shown in FIG. 2;

FIG. 13 is a partial enlarged view of portion 13 shown in FIG. 7;

FIG. 14 is a partial enlarged view of portion 14 shown in FIG. 8;

FIG. 15 is a front perspective view of the binder in an open state;

FIG. 16 is another front perspective view of the binder thereof;

FIG. 17 is a partial enlarged view of portion 17 shown in FIG. 15; and,

FIG. 18 is a partial enlarged view of portion 18 shown in FIG. 16.

The short evenly spaced broken lines in the figures depict environment and form no part of the claimed design. In addition, the dot-dash broken lines define the bounds of the enlargements and form no part of the claimed design.

1 Claim, 14 Drawing Sheets
